[57] CLAIM

The ornamental design for a check holder for key chain, as shown and described.

DESCRIPTION

FIG. 1 is a front view of a check holder for key chain showing our new design;

FIG. 2 is a back view thereof, being essentially identical to the front view;

FIG. 3 is a right side view thereof; the left side being a mirror image of the right side;

FIG. 4 is a top view thereof; and,

FIG. 5 is a bottom view thereof.
